HIGH FREQUENCY OSCILLATOR AND MODULATOR

Nils E. Lindenblad, Port Jefferson, N. Y., assignor to Radio Corporation of America, a corporation of Delaware

Application November 24, 1934, Serial No. 754,559

6 Claims. (Cl. 179—171)

This invention relates to oscillation generators and more particularly to a method of and apparatus for generating ultra high frequency oscillations.

5 Observations have shown that in using electron discharge devices in the generation of ultra high frequencies, the capacitive reactions at these frequencies reach such low values as to prohibit any appreciable voltage swings of the tube elements. The elements will, in other words remain rather inert and thus assert very little or no control on the electrons, electro-dynamically speaking, unless abnormal oscillating currents are used, which inherently is prevented by power 10 limitations. This will be especially true for frequencies above 500,000 kc. In the region between 400,000 and 500,000 kc., it has been found possible to help the conditions, in otherwise somewhat unsuitable tubes, by special tuning arrangements.

15 20 One of the objects of the present invention is to provide an improved oscillation generator for these short waves, and this is achieved, generally speaking, by making groups of electrons act in such a way as to control their own flow and pulsations, electro-dynamically more independent of the electrodes of the electron discharge devices; the function of the electrodes then being only to produce the electron emission condition required by the phenomena and to furnish momentum to 25 30 the electrons.

A specific object of the present invention is to provide an improved form of braking field or Barkhausen-Kurz oscillator of the type wherein a grid is maintained at a higher positive potential 35 relative to the other electrodes of the oscillator, and wherein electrons have a pendulum or to-and-fro motion about the grid.

A feature of the invention lies in the provision of an auxiliary grid in the electron discharge device between the regular grid and the cathode.

40 Other objects, features and advantages will appear in the subsequent detailed description which is accompanied by a drawing illustrating, diagrammatically, the improved oscillator of the 45 invention in connection with a complete transmitting circuit, given by way of illustration only. Although the oscillator of the invention is herein shown in a transmitting circuit, it will be understood, of course, that it is not limited thereto, since it may just as well be used in a receiving 50 circuit.

The drawing illustrates a cross sectional view of the oscillating electron discharge device comprising an evacuated envelope 1, enclosing an electron emitting cathode 2, a plate 4, a main grid 3

and an auxiliary grid 5. Envelope 1 is provided with four stems or presses 6, 7, 8, 9, each individual to an electrode so as to prevent undesirable capacitive reactions between electrodes. For reasons which appear later, auxiliary grid 5 is 5 arranged to be a closer mesh and screen affair than the main grid which is herein shown to be a rather open mesh structure. The plate 4 is shown to be of solid material throughout, but it is to be understood that since the bombardment 10 of this electrode from the electrons is very slight, if any at all, the structure can be made of some light screen material.

For producing oscillations it is preferred that the auxiliary grid 5 be maintained at a slightly 15 negative potential, the main grid 3 at a high positive potential and plate 4 at a somewhat negative potential, all relative to the cathode 2 which is at neutral or ground potential.

The theory underlying the production of oscillations will now be given. It is to be understood, however, that this theoretical explanation is given mainly for the purpose of exposition, and in order that the invention may be better appreciated. While this theoretical explanation 25 is believed to be correct, it is not of necessity complete, nor does the operation of the invention depend upon its accuracy or otherwise.

Due to the high positive potential on the main grid 3, electrons will be drawn from the cathode 30 2 toward grid 3 in spite of the slightly negative potential on the auxiliary grid 5. As these electrons travel toward the main grid 3, they will be accelerated, and a number of them will strike grid 3 and cause considerable heating of this 35 grid. It is believed that the electrons which strike the main grid detach other electrons from this grid, possibly influencing them to follow the remaining course of electrons which pass through the mesh of the main grid, thus adding secondary 40 emission effect to the braking field or Barkhausen-Kurz phenomena. The group of electrons which is mostly effective in causing oscillation generation, however, is the one that does not land on the main grid 3 but passes through it. 45 Immediately upon passing through the main grid 3, the velocity of the electron group will be retarded, inasmuch as the high positive main grid is now behind the negative electrons instead of ahead of them. If the potential of the plate 4 is 50 zero, the electrons will then have lost all their velocity upon arriving at the plate. Some of these electrons may land on the plate and will then produce a direct current component in its circuit. The electrons stopping in front of the 55

plate have the effect of repelling later arriving electrons sooner, while the latter cause the early electrons to be held over. The result is that the electrons turn around more nearly at the same time for their return travel, and thus organize themselves into a group. From the foregoing it will be evident that it is desirable to give the plate a somewhat negative potential, in which case the electrons will stop in space at such a point where the gradient between the positive main grid 3 and the negative plate 4 reaches zero. As soon as a negative layer of electrons is formed in this space, its negative potential will add to that of the plate and result in moving the zero point of the space voltage gradient farther towards the main grid.

In considering the phenomena occurring at the plate, it is found that, actually, there is a slight flow of current even when the plate is maintained at a negative potential, since some of the early arriving electrons are pushed into the plate by later arriving electrons. It must also be remembered that, due to the temperature of the cathode, the electrons will have a certain velocity given to them which is not due to space gradient. This initial momentum may make the electrons travel beyond the zone set by the zero of the voltage gradient and cause them eventually to reach the plate 4. The secondary emission from the hot main grid 3 may further add indirectly to this phenomena; thus electrons may be brought all the way to the surface of the plate in spite of its being at a negative potential. Irrespective of what takes place near the plate, a very small change in potential on the plate will decide whether electrons are to be drawn towards it or repelled from it. In this connection, the tuning of the plate aids in determining this condition.

As for the returning electrons on their journey back towards the main grid 3, it is believed that many of these electrons land on the wires of the grid, the remaining ones continuing towards the cathode under the retarding force exerted by the main grid. Since a considerable portion of the electrons originated at the cathode, they possess sufficient momentum to carry them back towards the vicinity of the cathode. They will, however, fall short of reaching the cathode since during their travel they have induced currents in the external circuit. The electrons have, therefore, given up some of their kinetic energy. Their oscillation is alternated, and their amplitude about the grid becomes smaller and smaller until they are finally lost in the grid. Of course only very few electrons live through a completely attenuated oscillation life. Most of them are lost on the grid during their early cycles. The group, as a whole, is not attenuated, since lost electrons are continually renewed. The group amplitude of oscillation assumes an average value of the individual electron oscillation amplitude. It can thus be seen that the group does not reach the cathode but forms a negative space charge at its turning point in front of the cathode, similar to the phenomenon in front of the plate, and thus reduces the emission from the cathode towards the main grid. The returning electrons reduce the emission to the main grid until they are themselves drawn towards that grid and repeat the procedure or cycle over again. The space charge around the cathode will then clear out at least partially and more emission will again be possible. This pulsation in the emission is helpful in further organizing the electrons into a group so that stray oscillations obtain in the external

circuit. It will thus be seen that the period of this type of oscillation is wholly independent of any tuning phenomena, but depends solely on the space gradients and emission densities, although it is known that mixed phenomena do occur and that the operation may be explained in a number of ways.

It will now be seen that the auxiliary grid 5 offers a means by which the space charge around the cathode may be controlled. Although the primary function of auxiliary grid 5 is to provide a condition under which the returning electrons may more completely shut off the emission from the cathode to the main grid and thus allow an increase in power output from the electron discharge device, still if the auxiliary grid is made to have a slightly negative variable potential the path of the electrons emitted from the cathode to the main grid may be so regulated that the electrons pass through a very narrow space in the center of the openings between each wire in the auxiliary grid. The returning electrons will also select this same center for their return passage towards the cathode as the centers have minimum negative potential. In this manner the narrow passageway will offer considerable stagnation and possibly complete shutdown of outgoing electrons from the cathode, which condition, if obtained, produces efficient power output from the electron discharge device.

For tuning the oscillator there are provided parallel tuned circuits 10 and 11 in the auxiliary grid and plate circuits respectively. Any suitable utilization circuit, such as an antenna 12, is shown electromagnetically coupled to the tuned plate circuit 11 through a transmission line 13. Potentiometers 16 and 17 enable variation of the voltages applied to auxiliary grid 5 and plate 4, respectively. A connection 18 extends between the potentiometer 17 and the main grid 3.

The Heising method of modulation is herein shown for modulating the oscillations, a modulation input circuit 14, which may be a telegraph key, or a speech circuit, being coupled to a vacuum tube 15 whose output is connected to the main grid 3 of the oscillator tube.

It will be understood that the structure set forth in the drawing is entirely illustrative and not definitive, since various changes may be made in the form, shape, and arrangement of the various elements and circuits without departing from the spirit and scope of the invention.

What is claimed is:

1. An oscillation generator comprising an electron discharge device having within its envelope a cathode, a plate, a grid between said cathode and plate, and an auxiliary grid between said cathode and first grid, and means for maintaining said first grid at a high positive potential and said auxiliary grid and plate at a slightly negative potential relative to said cathode, both said first grid and said auxiliary grid comprising screens, the screen of said auxiliary grid having a closer mesh than the screen of said first grid.

2. In combination, an oscillation generator of the braking field type comprising an electron discharge device having within its envelope a cathode, a plate, a grid between said cathode and plate, and an auxiliary grid between said cathode and first grid, a source of potential for maintaining said auxiliary grid at a slightly negative potential relative to said cathode, a parallel tuned circuit connected between said first grid and cathode, a connection including a parallel tuned circuit between said source and said aux-

iliary grid, means for maintaining said first grid at a high positive potential relative to said cathode, means for maintaining said plate at a much less potential than said first grid, and a parallel tuned output circuit coupled between said plate and cathode, said auxiliary grid being constituted by wires which are more closely spaced than the wires of said first grid, whereby substantially complete electron cut-off from said cathode to said first grid can be effected.

3. In combination, an oscillation generator of the braking field type comprising an electron discharge device having within its envelope a cathode, a plate, a grid between said cathode and plate, and an auxiliary grid between said cathode and first grid, a source of potential for maintaining said auxiliary grid at a slightly negative potential relative to said cathode, a parallel tuned circuit connected between said first grid and cathode, a connection including a parallel tuned circuit between said source and said auxiliary grid, means for maintaining said first grid at a high positive potential relative to said cathode, means for maintaining said plate at a much less potential than said first grid, a parallel tuned output circuit coupled to said plate, and means coupled to said first grid for modulating the oscillations produced, said auxiliary grid being constituted by wires which are more closely spaced than the wires of said first grid, whereby substantially complete electron cut-off from said cathode to said first grid can be effected.

4. In combination, an oscillation generator of the braking field type comprising an electron discharge device having within its envelope a cathode, a plate, a grid between said cathode and plate, and an auxiliary grid between said cathode and first grid, a source of potential for maintaining said auxiliary grid at a slightly negative potential relative to said cathode, a tuned circuit connected between said first grid and cathode, a

connection including a tuned circuit between said source and said auxiliary grid, means for maintaining said first grid at a high positive potential relative to said cathode, a conductive connection comprising a resistance connected between said first grid and said cathode, means for maintaining said plate at a much less potential than said first grid, a parallel tuned output circuit coupled to said plate, a connection from a point intermediate the ends of said resistance to the means for maintaining said plate at a desired potential, and means coupled to said first grid for amplitude modulating the oscillations produced.

5. In combination, an oscillation generator of the braking field type comprising an electron discharge device having within its envelope a cathode, a plate, a grid between said cathode and plate, and an auxiliary grid between said cathode and first grid, a source of potential for maintaining said auxiliary grid at a slightly negative potential relative to said cathode, a parallel tuned circuit connected between said first grid and cathode, a connection including a parallel tuned circuit between said source and said auxiliary grid, means for maintaining said first grid at a high positive potential relative to said cathode, and means for maintaining said plate at a much less potential than said first grid, said auxiliary grid being constituted by wires which are more closely spaced than the wires of said first grid, whereby substantially complete electron cut-off from said cathode to said first grid can be effected.

6. A generator in accordance with claim 1, including a resistance connected between said first grid and cathode, and a conductive connection from a point intermediate the ends of said resistance to said plate.
